UNITED STATES PATENT OFFICE.

CARL SCRABIC, OF URBANA, OHIO.

SOUND-BOX MOUNTING.

Application filed March 28, 1921, Serial No. 456,049. Renewed July 10, 1922. Serial No. 573,923.

To all whom it may concern:

Be it known that CARL SCRABIC, a citizen of the United States, residing at Urbana, in the county of Champaign and State of 5 Ohio, has invented certain new and useful Improvements in Sound-Box Mountings, of which the following is a specification.

This invention relates to an improved mounting primarily adapted for use in conjunction with talking machines for the purpose of providing an efficient connection between the sound box and tone arm members of such machines, the construction of the mounting being of such nature as to provide 10 means whereby the sound box may be securely yet detachably carried by the outer end of a tone arm; to include a construction whereby the metallic parts of the sound box and tone arm will be relatively insulated 15 to eliminate metallic vibration or chattering; to provide means for sealing the interior chambers of the sound box and tone arm in order that extraneous influences will not interfere with the free, proper and undisturbed 20 passage of the sound waves through the structure, and finally and more essentially to provide the mounting with features of construction whereby the sound box will have a vertical pivotal connection with the 25 outer end of the tone arm, in order that the stylus of the sound box may be perfectly centered within the groove of the record irrespective of irregularities in the curve characteristics of the groove, the mounting being 30 such as to normally maintain the casing substantially at right angles to the outer end of the tone arm and yet under abnormal conditions, to permit of the flexing of the sound box relative to the tone arm to compensate 35 for the irregularities mentioned.

With these and other objects in view, as will appear as the description proceeds, the invention accordingly consists in the novel features of construction, combinations of elements and arrangements of parts, and hereinafter to be fully described and pointed out in the appended claims.

In the drawing:

Figure 1 is a vertical sectional view taken 50 through the improved coupling comprising the present invention,

Figure 2 is a side elevation thereof,

Figure 3 is a transverse vertical sectional view taken on the plane disclosed by the line 55 3-3 of Figure 1,

Figure 4 is a detail perspective view of one end of the tone arm, and

Figure 5 is a similar view of the securing sleeve.

Referring more particularly to the details of the invention, the numeral 1 designates 60 a sound box of the type employed in conjunction with talking machines, and the numeral 2 designates the cooperatively associated tone arm, of the type employed for 65 conducting sound vibrations set up by the sound box to the usual amplifier construction, not shown. The sound box, in this instance, includes an annular metallic casing 70 3, in which is provided a diaphragm chamber 4, and the usual vibratory diaphragm 5 is adapted to be mounted for vibration within the chamber 4 and has its peripheral edges disposed for engagement with annular gaskets 6, which enable the diaphragm to 75 vibrate independently of the walls of the casing, the diaphragm and gaskets being maintained within the chamber 4 by the provision of a removable ring 7. The diaphragm is connected axially with the offset 80 upper end 8 of an oscillatory stylus member 9 which, in turn, is intermediately pivoted as at 10 to the lower part of the casing 3, the end 8 of the stylus member being properly maintained in contact or engagement 85 with the diaphragm 5 by means of a spring 11, which operates upon said stylus in such manner as to force the upper end thereof outwardly. The lower end of the stylus is provided with the usual needle 90 socket 12, in which a needle 13 may be removably mounted for engagement with the grooves of a record. It will be understood that in operation the stylus member will be oscillated by the engagement of the needle 95 with the record undulations, the vibratory movement thereof will be imparted to the diaphragm 5 in the usual manner, and the sound wave set up by the vibration of the diaphragm will then, in turn, be transmitted 100 to the communicating end of the tone arm 2, which end is designated by the numeral 14, in this instance is disposed to enter the rear side of the casing 3 centrally and axially through an opening 15 provided therein, in 105 order to be in open communication with the chamber 4. It will be understood that the sound waves are thence conducted by the tone arm to suitable amplifying beams.

The present invention aims to provide an 110

improved mounting or coupling for connecting the casing of the sound box with the end 14 of the tone arm, and to effect this result in such manner that while the 5 casing will be securely mounted in connection with the tone arm yet there will be no positive and direct metallic contact between the casing proper and the tone arm. This end is effected by forming the end 14 of the 10 tone arm with a fixed collar 16 which is slightly spaced from the extreme outer portion of the end 14. The periphery of this collar is provided with a pair of outwardly projecting studs 17, preferably, of substantially triangular formation. These studs are adapted to be positioned within bayonet slots 18 provided in a metallic sleeve 19 arranged to be rigidly carried by the rear wall of the casing 3, the interior of said 15 sleeve being of a diameter slightly exceeding that of the collar 16, in order that said collar may be received within the sleeve. The sleeve 19, in this instance, is formed at one end with a laterally projecting annular 20 flange 20, which is designed to engage with a flat annular gasket 21, which is arranged to be interposed between the flange 20 and the rear wall 22 of the casing 3. Fastening elements, in the nature of screws or the 25 like 23 are arranged to pass through the flange 20, the gasket 21 and to be threaded into the wall 22, in order that the sleeve 19 may be rigidly mounted in connection with the casing 3 and to be maintained in a 30 concentric position with respect to the longitudinal axis of said casing and the end 14 of the tone arm 2, the gasket 21 being utilized to avoid direct contact between the metallic wall of the casing and the flange 35 20, thus to prevent sympathetic vibration between these ordinarily metallic parts. Arranged to be positioned between the gasket 21 and the inner wall of the collar 16 is a compressible ring 24, of rubber or the 40 like, which is so positioned that when the studs 17 have been passed through the entrances 25 of the slots 18 and thence into the circumferentially extending portions 26 of said slots, the said ring 24 will be more or 45 less compressed, thus exerting an outwardly directed pressure on the sound box proper. Therefore, when the sound box has been 50 revolved to its maximum extent, the said studs 17 will be seated within the relatively 55 enlarged and closed inner ends 27 of the slots, and will be maintained therein by the resiliency of the ring 24, so that the said studs will be retained within the ends 27 in order to lock the sound box in its position 60 of application upon the end of the tone arm. Another gasket ring 20 is positioned in the outer end of the sleeve 19 and engages with one face of the collar 16 so as to close the outer end of the sleeve and to 65 prevent undue sound vibration therein.

In view of the foregoing description, when taken in conjunction with the accompanying drawing, it will be apparent that the present invention provides a novel and efficient mounting or coupling between the 70 sound box of a talking machine and the co-operating end of a tone arm. It will be observed that the construction will admit of the convenient positioning of the sound box upon the end of the tone arm and to 75 secure the same in connection therewith, the construction also serving to eliminate screws or other similar fastening elements. More essentially, however, the coupling avoids direct metallic contact between the 80 casing of the sound box and the companion parts of the tone arm and thus overcomes such undue vibration and interference with sound reproduction as will occur when metallic parts are directly and physically connected in engagement with one another.

It will be observed that the provision of the radially extending, vertically disposed knife edges provided by the stud 17, will produce a vertical pivotal connection 90 between the sound box and the outer end of the tone arm, which will permit of change in the angular relationship existing therebetween. Normally, the sound box casing will be positioned substantially at right 95 angles to the longitudinal axis of the outer end of the tone arm, and the compressible ring 24 will normally serve, by reason of its confined position, to maintain this relationship between the arm and the sound 100 box casing proper. However, in the event that the stylus of the sound box is traveling in a record groove of irregular or abnormal formation, the sound box is permitted to swing to a limited degree by reason of the 105 studs 17, in order that said sound box may have its stylus centrally positioned within the record groove so as to overcome undue friction between the walls of the groove and the stylus, and to thus enable the sound 110 box to faithfully reproduce the sound undulations provided in a record groove. It will be understood that when the turning or twisting pressure upon the sound box has 115 been removed, the ring 24 will automatically serve to return the sound box casing to its normal position.

What is claimed is:

1. In a talking machine, a sound box casing, an axially located sleeve rigidly carried 120 by and projecting from the back of said casing, a tone arm disposed axially within said sleeve, a collar formed with said tone arm and positioned within said sleeve, diametrically opposed studs projecting from 125 said collar and received within bayonet slots formed in said sleeve, and resilient means interposed between said collar and casing and serving to oppose the turning movement of said casing upon said studs. 130

2. In a talking machine, a sound box casing, a sleeve mounted upon the back wall of said casing and projecting axially therefrom, a tone arm arranged to be axially received within said sleeve, a wall formed with said tone arm, studs having knife edges projecting from said wall and arranged to be received within bayonet slots provided in said sleeve, and compressible means located between said wall and said 10 casing and serving to resist turning movement of said casing about said studs.
- 5 In testimony whereof I affix my signature.

CARL SCRABIC.
